UNITED STATES PATENT OFFICE.

JOHN T. PHIPPS, OF HUNTINGTON PARK, CALIFORNIA.

OPERATING HEAD FOR PUMPS.

Application filed April 15, 1925. Serial No. 23,257.

To all whom it may concern:

Be it known that I, JOHN T. PHIPPS, a citizen of the United States, and resident of Huntington Park, in the county of Los Angeles, State of California, have invented new and useful Improvements in Operating Heads for Pumps, of which the following is a specification.

This invention relates to an operating head for reciprocating pumps and is especially adapted for deep well pumps. The weight of sucker rods, depending parts, and the column of liquid on deep wells such as oil wells is of such magnitude that the change in the direction of movement at the end of the down stroke must be gentle, and, it is preferable that there be a period of rest so that the parts may settle before the return stroke. At the end of the up stroke, since gravity acts against the load being carried, it is preferable that the change in direction be as quick as possible in order to increase efficiency. Another important factor in pumping oil wells is the length of stroke. It has been found that the production of oil wells is increased by increasing the pump stroke. To the end that a long stroke may be attained with a minimum of change in the machinery now employed, it is desirable that a straight movement operating head be provided.

The primary object of this invention is to provide an operating head which will convert the rotary motion of an engine into the reciprocating motion of a pump, and wherein the motion of the pump may be designed to produce the result above mentioned.

These objects together with other objects and corresponding accomplishments are obtained by means of the embodiment of my invention illustrated in the accompanying drawing, in which:

Fig. 1 is an elevation of the upper end of a deep well pump, with my operating head mounted thereon; Fig. 2 is a section as seen on the line 2-2 of Fig. 1; and Fig. 3 is a section as seen on the line 3-3 of Fig. 1 showing a fragment of the structure.

Referring more particularly to the drawing, 5 indicates a well casing within which is mounted the pump tubing 6. The sucker rod is indicated by 7.

Mounted upon a head 8 or any other suitable structure is a frame 9 having vertically disposed slide rods 10. Mounted so as to

be reciprocated upon the rods 10 is a carriage 11 to which the sucker rods 7 are attached. There is formed in one face of the carriage plate a channel of endless shape ⁶⁰ having teeth 12 on the outer wall thereof. This recess is of triangular shape having a flat upper side or base and an apex at the lower end. Back of the channel is a recess ⁶⁵ 13 of corresponding shape. This recess is to receive the stub end of a shaft. Intermediate the bottom and top of the frame is a bridge 14 having rails 15 at the top thereof, upon which is slidably mounted a block 16. Journalled upon block 16 is a shaft 17, upon ⁷⁰ the stub end of which is mounted a roller riding in recess 13. Fixed to the shaft is a pinion 18 connected with the teeth 12.

The shaft 17 is connected to a shaft 19 by means of a universal joint 20, and shaft 19 may be connected through a universal joint 21 and other well known mechanical means to a drive pulley shaft 22, the pulley being indicated by 23. Pulley 23 is suitably ⁷⁵ geared to a source of power.

It will be obvious that rotation of the pulley 23 will convey rotary motion to the shaft 17. This causes the pinion 18 to be rotated and the carriage 11 to be correspondingly reciprocated. The pinion is maintained in ⁸⁰ mesh with the teeth 12 on the carriage by reason of the stub end of shaft 17 being guided in the recess 13.

There is an even uniform feed of the carriage from the apex to the base of the triangle. A uniform speed of the down stroke is imparted to the sucker rods, column of liquid, and other parts. The stroke is finished when the pinion reaches the base of the triangle. At this point reciprocatory ⁹⁰ movement ceases, and a period of rest occurs while the pinion is moving to the opposite leg of the triangle. This period permits all of the parts and the column of oil to settle. Thereupon, the carriage starts to move in ⁹⁵ the opposite direction on the up stroke. Thus, there is a period of rest at one end of the stroke which may be made as long as desirable, and a quick change in direction at the other end of the stroke.

What I claim is:

1. In a reciprocating operating mechanism of the character described, the combination of a frame, a carriage mounted to be reciprocated therein, said carriage having an endless internally toothed track provided at one end with a substantially

- straight portion transverse to the path of the path of reciprocation of said carriage, a transverse guideway on said frame, a block laterally slidably mounted on said guideway, and a driving shaft journaled on said block and having a gear thereon in engagement with 15 said track.
- 5 2. In a reciprocating operating mechanism of the character described, the combination of a frame, a carriage mounted to be reciprocated therein, said carriage having an endless internally toothed track of tri-
- 10 angular form with the base transverse to

In witness that I claim the foregoing I have hereunto subscribed my name this 10th day of April, 1925.

JOHN T. PHIPPS.
